Specification of Letters Patent.

Patented May 30, 1916.

Application filed October 27, 1909. Serial No. 524,936.

To all whom it may concern:

Be it known that we, ALBERT BALL and MORRIS P. HOLMES, both citizens of the United States, and residents of Claremont, 5 in the county of Sullivan and State of New Hampshire, have invented an Improvement in Mining-Machines, of which the following description, in connection with the accompanying drawings, is a specification, 10 like letters on the drawings representing like parts.

This invention relates to mining machines and more particularly though not exclusively to machines of the cutter chain type, 15 which are fed along the face or side of the wall in which the cutting is being made.

Among the objects of our invention are improved means for controlling and feeding such machine, and improved constructional 20 features which provide a machine of compact form, great strength and effectiveness and convenience of arrangement.

Our invention will be best understood by reference to the following description, when 25 taken in connection with the accompanying illustration of one specific embodiment thereof, while its scope will be more particularly pointed out in the appended claims.

30 In the drawings: Figure 1 is a plan view partly broken away, showing the principal working parts of a mining machine embodying one form of our invention. Fig. 2 is an outside or rear elevation of the mining 35 machine shown in Fig. 1. Fig. 3 is a transverse section in elevation on the line 3—3 in Fig. 1. Fig. 4 is a transverse section in elevation on the line 4—4 in Fig. 1. Fig. 5 is a longitudinal sectional elevation on the 40 line 5—5 in Fig. 1. Fig. 6 is a detail in plan of the central supporting member for the cutter bar. Fig. 7 is a transverse section in elevation showing the supporting member. Fig. 8 is a plan view of a portion of the 45 main frame. Fig. 9 shows in elevation the arrangement of the reversing and driving gearing for the valve shaft. Fig. 10 shows a section in plan on the line 10—10 in Fig. 9. Fig. 11 is a detail of the holding 50 pin for the swing arm brace; and Figs.

12, 13 and 14 are diagrammatic representations showing the machine with its cutter bar and feeding mechanism in different relations.

Referring to the drawings and to the embodiment of our invention selected for purposes of illustration, there is disclosed an air driven chain mining machine of the so-called "long-wall" type, adapted to make a continuous cut while traveling close to the face of the wall, the top of the mine being either posted or permitted to drop, except in the narrow space in which the machine travels.

While we have shown our invention embodied in such a type of machine, it is to be understood that it has application as to many of its features to machines of other types and constructions and employing other forms of motive power.

Referring to the drawings, the machine there illustrated has the body or main frame member 1 with a cutter bar 2 projecting therefrom transverse to the direction of greatest length and preferably inclined 75 slightly toward the direction of machine travel. The cutter bar as usual carries a suitable cutter chain 3 which, together with the bar, may be of any usual or well known construction. The cutter chain is moved as 80 usual by a sprocket wheel 4, the latter driven in turn through suitable power transmission gearing by the engine or motor on the machine.

While for such purposes any suitable construction may be employed, in the present machine supporting means are provided upon and with which the machine is adapted to move along the mine preferably, as herein shown, in the form of a bottom member of shoe 5, upon which the machine is adapted to slide, if desired, directly upon the bottom or floor of the mine.

In order to hold the cutter chain and the cutter bar in the desired relation against the work as the machine is fed along, guiding means are provided, the same consisting of a chain, cable or other appropriate flexible guiding means, preferably kept under tension and so associated with the machine that 100

the cutter bar as it travels is held up to the work without the actual necessity of rails or other like guiding supports, although the latter may be employed if desired.

- 5 In the illustrated form of the invention there is provided for this purpose a flexible guiding means either in the form of a cable chain 6, comprising two portions or lengths 7 and 8, one passing to the advancing side of 10 the machine and the other to the receding side thereof, (see Figs. 12 and 13), whereat each is connected to a fixed support. One portion is connected to the machine adjacent its wall or cutting end and the other 15 near the opposite or rear end thereof. In the illustrative embodiment of the invention these two lengths or portions 7 and 8 form parts of a single unbroken cable length one end of which is drawn into the machine as 20 the other end is paid off.

As seen in Figs. 1 and 12, the leading cable length 7 on the advancing side of the machine, passes first to and about a guiding sheave 9 journaled about a substantially upright axis preferably near the foremost inner or wall corner of the machine. Thence the chain passes about the horizontal guiding sheave 10 and the slightly inclined sheaves 11 and 12 to the feed driving member 13 of the machine which herein consists of a sprocket wheel located near the rear or cutter-bar-end of the machine and driven by appropriate power transmission mechanism.

The guiding sheaves 11 and 12 are located 35 near the corners of the machine so that the chain is caused to travel from the sheave 9 to the sprocket wheel along the outside of the machine. From the sprocket wheel 13 the chain passes to a guide sheave 14 carried 40 by suitable support arm 15 and located near the outer corner of the machine.

The free end of the leading chain portion is secured to a suitable anchor 16 (Fig. 12) while the end of the receding or trailing chain portion is secured to a fixed and preferably adjustable support such as the take-up jack 17, similar to the take-up jack described in the prior patent to Mitchell, No. 656,414. The two cable portions, therefore, 50 when under tension and with the cutter chain engaging the coal, serve to hold the cutter bar in its assigned position and the latter can be regulated by adjusting the tension on the trailing cable 8 to swing the machine more or less about the guiding sheave 9 as a fulcrum. Herein by the employment 55 of the power driven sprocket wheel engaging the chain, the machine is drawn along its flexible guide and automatically given 60 its own traversing feed, so that in the preferred embodiment of the invention herein illustrated and described the chain performs the function of feeding the machine as well as of guiding the same.

65 Referring to the connection of the cutter

bar to the machine, the bottom shoe 5 extends preferably for the entire width and extent of the frame member 1, the latter at the rear or cutter bar end being so formed as to provide a space above the shoe in which the cutter bar is swiveled. The cutter bar is provided at its inner end with a removable cap piece 18 by which it may be secured to a pivotal support 19, the latter being in the form of a flanged sleeve riveted to or otherwise secured to the shoe.

The cutter bar is so arranged that it may be locked in cutting position at either side of the machine, so that the machine may be used for cutting in either direction, or the bar may be locked lengthwise the machine for convenience in transportation or for the purpose of making a starting or sumping cut if desired. As shown in Figs. 1 and 3, the frame plate is provided at each side with 85 an opening 20 adapted to receive a locking pin 21, which also enters a suitable opening in the cutter bar when the latter is brought into the proper position for cutting. The locking holes 20 are located slightly in front 90 of a true right angled relation so that the bar when locked in position is inclined forward a few degrees in the direction of cutting, thereby serving better to hold the traversed machine into the coal. The lower end 95 of the locking pin 21 fits into a recessed holding plate 22, secured to the shoe 5 and is held therein against displacement by means of the locking bolt 23.

When it is desired to reverse the cutter 100 bar and cut on the opposite side of the machine, the locking pin is removed, the bar swung around to the opposite side of the machine and locked thereat as shown in Fig. 13, the cutter bits being also reversed 105 on the cutter chain. The supporting arm 15 for the guide sheave 14 is swiveled upon the frame so that in this relation of the cutter bar the connection of the feeding and guiding chain can also be completely 110 reversed. The supporting arm 15 is held fixed in its assigned position by means of the brace arm 24 jointed to the supporting arm at its outer end and having a slot 25 at its inner end which may be slipped over an upright 115 hooked shaped stud 26, (see Fig. 11) one such stud being secured to the frame of the machine at either side so that the sheave arm may be swung to and fastened in either the position shown in Fig. 12 or that shown in 120 Fig. 13. The stud is shown in detail in Fig. 11.

The supporting arm at its inner end (Figs. 5 and 7) is swiveled upon the upright stud 27, the latter secured in the frame 125 member 1 where it overhangs the end of the bottom shoe. The stud 27 rests upon a post 28 to which is secured by means of the bolt 29 the post which latter serves as a distance and supporting member for the end of the 130

frame relatively to the shoe. If it is desired to swing the cutter bar and fasten it in a central position lengthwise the machine, it is fastened therein by the post 28 which is caused to enter and engage the locking opening 30 in the cutter bar (see Fig. 1). The lower end 31 of the post is necked down at 32 so that it can enter an arc-shaped slot 33 in the holding plate 34 fastened to the shoe 5. The edges of the slot overlie the end 31 of the post so as to hold the same in position except when the post is removed through the open end of the slot. When it is desired to lock the cutter bar in its central position the post 28 is free by unscrewing the bolt 29 and it is then drawn out from the holding plate and inserted in the locking opening 30 of the cutter bar. The bar is then unlocked from its side position 20 and swung around to its central position until the lower end of the post swings into the slot 33 and is held and positioned by the holding plate. The bolt 29 which has been held up out of the way by the lifting 25 spring 35 is then screwed down to lock the bar fast.

It will be observed that the guiding sheave 12 for the feed chain has a complementary guide sheave 36 located at a corresponding point on the opposite side of the machine. Such sheave is idle when the machine is arranged to cut as shown in Figs. 1 and 12, but is utilized when the cutter bar and the feeding connections are reversed as shown in Fig. 13, the sheave 12 being then the idle sheave. That is to say not only is the cutter bar reversible so that the machine can cut in either direction, but the feeding and guiding connections are also reversible 40 and preferably symmetrical with reference to the center line of the machine so that by swinging the guide sheave 14 to a reverse position and reversing the relation of the chain to the series of guiding sheaves, the machine can quickly be prepared for reverse cut. For example, when the cut has been completed with the machine arranged as shown in Fig. 12, the cutter bar can be reversed, the run of the chain through the 45 guide sheaves altered, the cutter bits reversed and the machine itself turned half way around as shown in Fig. 13, where it is prepared for repeating the cut in the reverse direction.

55 If it is desired to make a starting cut with the machine the cutter bar may be locked in a central position, as shown in Fig. 14, and, with or without the employment of the usual starting frame or other 60 guiding means, the machine may be made to draw itself into the coal by anchoring the free end of the chain at 59 near the face of the coal.

Referring now to the structure of the machine, it is to be noted that the frame plate

1 not only forms a bed plate for the engine at the forward end of the machine, but extends rearwardly as a single unbroken member suitably braced and strengthened, overhanging the cutter bar as described, and 70 forming a support for the superposed power transmitting mechanism. At the rear end of the machine there is formed an open space between the frame and the shoe, obstructed only by the post 28, through which 75 space the cutter chain moves and the coal cuttings pass.

The engine may be of any suitable construction, but herein we have provided a compressed air engine with its cylinders 80 arranged transversely the greatest length of the machine, thereby securing the minimum width of machine while permitting the employment of three cylinders and securing the resultant advantages of a three-cylinder 85 engine. Such arrangement also serves better to bring the reversing and other controlling devices at the end of the machine where they are always accessible, irrespective of the posting of the mine, while at the same 90 time, it permits a simple and better disposition of the power transmitting gearing.

The transmission of power is obtained (Figs. 4 and 5) from the engine crank shaft 37 through the gears 38 and 39 to the main 95 driving shaft 40. The latter drives the upright power shaft 41 through the beveled pinion 42 and beveled gear 43, the latter keyed to the power shaft and adapted to be clutched to or unclutched from the sprocket wheel 4 by means of a usual clutching device 44 common in this class of machine. The frame member is so fashioned at 45 as to provide what is practically a running fit for the edge of the beveled gear completely closing the gearing chamber above 100 from the cutter bar space, so as to exclude dirt and cuttings from access to the gearing above.

The frame member is not split or separated 110 through the axis of the upright power shaft as has been customary in machines of this type, being formed in a single piece (see Fig. 8), and being provided with the central opening just large enough to receive the 115 beveled gear at 45, this permitting the assemblage of the remaining gearing. When the parts are assembled, this opening is closed by means of the plate 46 which also provides an upper bearing for the power shaft 120 41, the lower bearing therefor being provided by the cutter bar support 19.

The sprocket wheel 13 is journaled on an upright stud 47, and is located preferably, near the rear center of the machine. To 125 drive the sprocket wheel from the power shaft, transmission gearing is provided of any well known or usual type, whereby, as is customary, the machine may be driven at either one of a plurality of speeds and pref. 130

erably through frictional or other yielding transmission devices. The details of the feed gearing are indicated on the drawings, but since they are not herein claimed, further 5 description is unnecessary.

Referring to the compressed air supply, the latter is received through the inlet opening 48 which is connected with any suitable source of supply ordinarily through a flexible hose pipe. In the present instance, the inlet opening 48 communicates with an air receiving chamber 49 of considerable volume which is provided by coring out the frame member beneath the cylinders as indicated 10 in Figs. 1 and 4. From such chamber the air supply passes through openings 50 in the frame member to suitable passages connected with the engine admission chambers, such passages not being herein shown. The 15 volume of the receiving chamber being appreciably large as compared with that of the cylinders and having preferably, though not necessarily, a capacity of not less than two of the cylinders combined, there is maintained an even supply pressure to the engines 20 irrespective of their pulsations. This is of marked advantage in a traveling machine where the larger sizes of hose are stiff and heavy and difficult to handle. The use of 25 the receiving chamber permits the employment of a smaller supply hose than could be used where the pressure fluid is supplied directly to the engines and without the interposition of a receiving chamber.

Referring now to the engine reversing means, we have provided devices for reversing the engine without the necessity of the usual eccentrics or eccentric connections which latter take up an amount of space not 30 easily spared in this type of machine. The reversing mechanism is also so arranged that it can be controlled from the end of the machine.

Referring to Figs. 1 and 9 to 10, inclusive. 35 the engine is provided with a separate valve crank shaft 51 which has a gear 52 driven from gear 53 on the main drive shaft 40. The gear 53, however, instead of being driven directly from the shaft 40 is mounted upon 40 an extension of the hub of the gear 39 and is driven by that gear through a suitable connection providing for a certain amount of lost motion. For this purpose the gears 53 and 39 are provided with interlocking 45 projections 54 and 55, respectively, through which the latter is adapted to drive the former in either direction. Lost motion, however, is provided for as indicated in Fig. 9, so that, when the machine is at rest, 50 if the gear 54 is turned ahead of the gear 55, the valve operating shaft will be advanced by approximately 120° and will start the engine up in a reverse direction. For 55 example, as shown in Fig. 9, the gear 39 is turning in the direction of the arrow and

driving the gear 53 through engagement between the projections 54 and 55 at the point 56. If the engine is brought to rest, however, and the gear 53 is moved to bring the projection 54 against 55 at the point 57, the 60 valve operating shaft will be moved by a sufficient amount to start up the engine in a reverse direction. The gear is thus moved to reverse the engine by merely turning the valve operating shaft itself, the latter, for 65 this purpose, being extended through the front wall of the frame member so as to present an end 58 suitably fashioned to receive a wrench or other implement for turning the shaft as described.

While we have herein shown and described one form of the invention as embodied in one particular type of mining machine, it is to be understood that not only as to constructional details and form and relative 75 arrangement of parts, but as to the embodiment or application made of various features of the invention, extensive modifications and departures from the described form may be had.

Claims:

1. A mining machine comprising in combination, a frame, a cutter bar pivotally mounted relative to said frame and adapted to be swung from one side thereof to the other, a shoe for said machine adapted to slide along the mine bottom during the operation of said machine, flexible advance and rearwardly extending guiding and feeding means and connecting means providing for reversal relative to said frame of the operative relation of said flexible advance and rearwardly extending guiding and feeding means when the position of the cutter bar relative to said frame is reversed.

2. A mining machine comprising, in combination, a frame, a cutter bar projecting from said frame, a cutter chain, a pivotal mounting for said cutter bar whereby it may be swung relatively to said frame, means for securing said bar in adjusted position, a flexible guiding and feeding member engaging said frame at a point adjacent the side of the machine from which the cutter bar projects and adjacent the advance end of the machine, said flexible guiding and feeding member engaging said frame at a point adjacent the opposite side of the machine and adjacent the receding end thereof, operating means on the machine to engage said flexible guiding and feeding member and means to reverse said operating means when the cutter bar is swung into reverse position, whereby the same relative relation to said cutter bar may be maintained.

3. A mining machine comprising in combination, a frame, a cutter bar adapted to be secured in projecting relation to said frame on either side thereof, a shoe for said machine adapted to slide along the mine bot-

- tom during the operation of said machine, flexible advance and rearwardly extending guiding and feeding means and connecting means providing for reversal relative to 5 said frame of the operative relation of said flexible advance and rearwardly extending guiding and feeding means when the position of the cutter bar relative to said frame is reversed.
- 10 4. A mining machine having cutting means and flexible guiding means, fulcrum- 65 ing guide connection for the guiding means near the forward wall corner of the machine, and reversing means for the guiding means 15 including a guide for the guiding means near the rear outer corner of the machine and means permitting the last named guide to be shifted toward one side or the other of the machine.
- 20 5. A mining machine comprising, in combination, a frame, a cutter bar projecting from said frame, a cutter chain, cutter bar holding means providing for holding said cutter bar in fixed relation to said frame at 25 either side of said frame, a flexible guiding and feeding member engaging said frame at a point adjacent the side of the machine from which the cutter bar projects and adjacent the advance end of the machine, said 30 flexible guiding and feeding member engaging said frame at a point adjacent the opposite side of the machine and adjacent the receding end thereof, operating means on the machine to engage said flexible guiding 35 and feeding member, and means to reverse said operating means when the cutter bar is swung into reverse position, whereby the same relative relation to said cutter bar may be maintained.
- 40 6. A mining machine comprising, in combination, a frame, a cutter bar movable from one side of said frame to the opposite side thereof, means for securing said cutter bar in adjusted position, flexible guiding and 45 positioning means, rotary means engaging said flexible guiding and positioning means, and a plurality of fulcrums so organized and arranged relative to the machine and relative to each other that said flexible guid- 50 ing and positioning means may operatively engage said frame at substantially diagonally opposite portions of said frame, said fulcrum being positioned on opposite sides of the machine, whereby the flexible guid- 55 ing and positioning means may be arranged on the side of the machine opposite that from which the cutter bar projects.
7. A mining machine having a guiding and feeding chain, a driving sprocket wheel 60 engaging the same located centrally on the machine, and means connecting said chain to the machine including a guide member at either side of the machine having provi-
- sion permitting the chain to be reversed to drive the machine in either direction. 65
8. A mining machine having a cutter bar, an undivided frame member above the cutter bar, an engine, a shaft transmission gearing between said engine and said shaft, said frame member having a central opening to 70 provide for the assemblage of the transmission gearing, and a plate closing the said opening.
9. A mining machine having cutting means, machine propelling means, flexible 75 guiding means presenting a pair of guiding members connected each to a fixed support one on the advancing side of the machine and the other on the receding side thereof and connected to the machine one near the 80 wall or cutting end and the other near the opposite end thereof, and means for reversing said guiding means including a guide for the receding member and means permitting said guide to be shifted from one side 85 of said machine to the other to receive said guiding means.
10. A mining machine having cutting means, machine propelling means, flexible 90 guiding means presenting a pair of guide members connected each to a fixed support one on the advancing side of the machine and the other on the receding side thereof and connected to the machine one near the 95 wall or cutting end and the other near the opposite end thereof, said machine being provided with a fulcrum guide for said guide means at each forward corner of the machine and a guide at each diagonally opposite corner therefrom and an adjustable 100 guide whereby said machine may be connected to said guiding means to move in either direction.
11. A mining machine having cutting means, means permitting said cutting means 105 to be positioned at either side of the machine, flexible guiding means presenting a pair of guide members connected each to a fixed support one on the advancing side of the machine and the other on the receding 110 side thereof, and reversing means for said guiding means including a guide member adapted to be positioned at either side of the center line of the machine whereby the guide means in engagement therewith may 115 be connected to the machine near the wall side or near the opposite side thereof.
- In testimony whereof, we have signed our names to this specification, in the presence of two subscribing witnesses.
